ALFRED STONE, OF ELMHURST, CALIFORNIA.

DOOR-LOCK.

1,110,725.

Specification of Letters Patent. Patented Sept. 15, 1914.

Application filed March 11, 1914. Serial No. 823,993.

To all whom it may concern:

Be it known that I, ALFRED STONE, a citizen of the United States, residing at Elmhurst in the county of Alameda and State of California, have invented certain new and useful Improvements in Door-Locks, of which the following is a specification.

This invention relates to improvements in locks, and has for its principal object the construction of device of the character specified having a combined lock and latch.

Another object is to provide a mechanism, which is operated by a push or pull on the handle according to the direction in which the door swings.

A further object is to provide a device, which when locked from one side cannot be unlocked from the other side. In general I have produced a simple effective mechanism especially applicable to interior doors, such as hotel rooms where it is desired that when the room is occupied the door cannot be opened from the outside.

With these and other objects in view my invention consists in the new and novel combination of parts as herein described and pointed out in the appended claims.

Reference is to be had to the accompanying drawings wherein,

Figure 1 is a view in elevation looking at the edge of the door having my improved lock applied thereto. Fig. 2 is a view in horizontal section through the improved lock. Fig. 3 is a view in section on the line 3—3 Fig. 2. Fig. 4 is a view in elevation showing the lock mechanism of one side of the device. Fig. 5 is a view in section on the line 5—5 Fig. 2. Fig. 6 is a view in section on the line 6—6 Fig. 4.

Referring to corresponding parts by the same numerals of reference, 1 denotes the door, 2 the frame therefor, 3 the stop strip, and 4 denotes a tubular casing preferably square in section in one end of which is pivoted at 6 the latch 5. A face plate 7 is attached to the tubular casing 4 and has an opening through which the latch 5 projects, and 8 is a strike plate with an opening 9 for the latch 5. Plate 7 is constructed with a laterally extending flange 10 adapted to extend over the edge of the strike plate 8 and thus prevent any thin tool from being inserted in the crack between the plates 7

and 8 and in this manner pry back the latch 5.

Pivotedly mounted in a recess in bolt 5 is a link member 11 provided with a slot 12 wherein is pivoted a roller 13. The rear end of 11 is slotted as shown at 14 and seated therein is a spring 15 mounted upon the pin 16. This spring serves to urge the bolt forward and at the same time act as a guide for the rear end thereof.

17 denotes a rectangular spindle slidably mounted in outer side walls of casing 4 and on one side of this member is provided an inclined surface 18. A roller 13 is pivotedly mounted in casing 4 on the other side of 17 so that when the latter slides in the direction of the arrow and the inclined surface 18 contacts with roller 13, the roller 13' takes the thrust. The movement of 18 pulls back link 11 and withdraws latch 5 from the opening 9 in plate 8.

On the two sides of the door are mounted casings 19 and 20 wherein are pivotedly mounted the handle levers 21 and 22. The former member is pivotedly mounted in the bottom of plate 19 and normally rests against plate 30 while the latter is pivotedly mounted in the top plate 20 and normally rests against the outer wall of this plate. Thus handle 21 may be pulled outwardly in which direction the door swings while the handle 22 must be pushed inwardly also in the direction of the door swing. These two plates are clamped together by means of a special screw 23, which passes through a slotted opening in plate 19 and engages a threaded lug in plate 20. This screw is provided with a slotted opening 25 intermediate its length, the slot being disposed in the plane of the slot in the head so that in erecting it may be positioned with the opening at right angles to the edge of the door and the nail 26 driven therethrough to prevent its removal.

Adjustment is provided for different widths of the doors by attaching the member 17 to the handle lever 21 through the medium of an eye bolt 27 in threaded engagement with one end of the bolt 17, the eye portion being pivotedly mounted in the handle lever as at 28. On the other end of 17 is provided a screw 29, the head of which abuts against the inside of the handle lever

22. Thus by adjusting the eye 27 and screw 29 various thicknesses of door may be accommodated and at the same time member 17 kept central in the tubular casing.

5 Attached to the entire surface of the casings 19 and 20 are plates 30 whereon is mounted the locking mechanism. This mechanism consists of an irregular shaped plate 31 pivotally mounted as at 32 held 10 against outward movement by the head of screw 33. On the lower end of plate 31 is formed a block 34, which is adapted to enter a notch 35 in the handle lever 21 or between the screw head and end of 17 on the opposite side. This plate is urged into these notches by means of springs 36, and on the lower end is provided a notch 37 contacting with the rectangular key 38 on the side of push button 39. This push button extends 15 through openings in the outer casing and plate 30 and is held normally raised by a flat spring 40. On one side of plate 31 is a projecting arm 41, which when the door is locked swings to a point opposite block 42. This block is provided with a number of corrugations 43 and an opening is provided in the plates 19 and 20 through which a key 44 may be inserted. This key is grooved to fit the corrugation of block 42 and the point 20 beveled as shown at 45 so that when it contacts with the arm 41 the latter will be depressed and plate 31 is moved to withdraw block 34 from the path of spindle 17. The end 46 projects across the path of the key 38 when the door is locked and prevents the bolt 39 from returning to its normal position. The handle levers are held in their normal position by a spring 47 coiled upon a pin 48 extending through the lower end 25 of the handle lever 21 and having the free ends resting against plate 19 and in use when the handles are pulled or pushed against the action of this spring member 18 contacts with roller 13 and further movement pulls the link inwardly drawing the latch 5 from the opening in the plate 7.

To lock the device after the door is closed either of the buttons 39 is pressed inwardly. This pushes the key 38 past the plate 31 allowing the spring 36 to move this plate toward the center of the mechanism bringing block 34 in the path of the sliding mechanism. It will be apparent that if one or the other of the handle levers are prevented 30 from moving the latch 5 can not be withdrawn thus forming an effective lock. It will also be apparent that as the locking mechanisms on the two sides of the door are independent that when locked from one side it will be necessary to open it from that side, which makes this lock particularly applicable on the doors of hotel rooms. To unlock the key is inserted through the opening and plate 42 and pushed against 35 arm 41, which depresses the plate 31 draw-

ing 34 from the notches and moving 46 past the key 38 allowing spring 40 to pull out the button 39.

What I claim as new and wish to cover by Letters Patent is:—

1. In a lock of the character described comprising the combination with a casing, of a latch pivotally mounted adjacent the outer end thereof, a slotted bar pivotally secured to said latch, a spindle slidable through said casing, an inclined surface on said spindle, a roller pivotally mounted in said slotted bar, said roller being adapted to contact with said inclined surface, spring means mounted adjacent the inner end of said casing and serving as a guide for the other end of said slotted bar, and pivotally mounted handles, adapted to move to and from the door and impart a sliding movement to said spindle. 70

2. In a lock of the character described comprising in combination with a casing mounted in the door, of a latch pivotally mounted in said casing, a slotted bar pivotally attached to said latch, a spring pivotally attached to the rear end of said bar, a spindle slidable through the slot in said bar and through openings in said door and casing, operative connections between said spindle and the door handles, said handles being pivotally mounted to move to and from said door, said operative connections comprising an eye bolt in threaded engagement with one end of said spindle and pivotally attached to the handle adapted to be pulled, a screw engaging the other end of said spindle and contacting with the handle adapted to be pushed, an inclined surface on the side of said spindle, a roller pivotally mounted in said slotted bar and contacting with said inclined surface and spring means for holding said handles in their normal position. 90

3. In a lock of the character described comprising a casing, a latch pivotally mounted in the outer end thereof, a slotted bar pivoted to said latch, a spindle slidable through the walls of said casing, an inclined surface on said spindle, said surface contacting with said bar to withdraw said latch handles adjustably connected to said spindle and adapted to impart a reciprocating movement thereto, notches in said reciprocating parts, and spring actuated lock plates adapted to move into said notches to 110 prevent the movement of said reciprocating parts. 115

4. In a lock of the character set forth comprising a casing, a latch, a sliding spindle mounted in said casing and adapted to operate said latch, locking means on each side of said casing comprising a plate movable across the path of said sliding spindle, a spring urging such movement, a catch formed in said plate, a shoulder on said but- 120 125 130

ton adapted to engage the catch of said plate when said button is raised, spring means for raising said button, an arm on said plate adapted to contact with the beveled end of a key and to be moyed thereby to withdraw said plate from the path of said sliding parts.

In testimony whereof I affix my signature in presence of two witnesses.

ALFRED STONE.
